J. G. HARRIS ET AL

AUTOMATIC PRESSURE VALVE

Filed April 18, 1922

Inventor
Joseph G. Harris and
George D. Jaquett.

By *Geo. P. Kimmel*,
Attorney

UNITED STATES PATENT OFFICE.

JOSEPH G. HARRIS AND GEORGE D. JAQUETT, OF JACKSONVILLE, FLORIDA.

AUTOMATIC PRESSURE VALVE.

Application filed April 18, 1922. Serial No. 554,645.

To all whom it may concern:

Be it known that we, JOSEPH G. HARRIS and GEORGE D. JAQUETT, citizens of the United States, residing at Jacksonville, in the county of Duval and State of Florida, have invented certain new and useful Improvements in Automatic Pressure Valves, of which the following is a specification.

This invention relates to shut off valves, more particularly to devices of this character for automatically shutting off the intake passage of gas or the like in event of the pressure being reduced below a certain predetermined or "safe" degree, or of the gas ceasing for any reason to flow, to prevent the escape of gas when the pressure is restored.

Another object of the invention is to provide a device of this character including a pressure influenced diaphragm and a gas controlling valve, and means whereby the gas controlling valve and diaphragm are operatively associated.

With these and other objects in view the invention consists in certain novel features of construction as hereinafter shown and described and then specifically pointed out in the claim, and in the drawings illustrative of the preferred embodiment of the invention:—

Figure 1 is a vertical section.

Fig. 2 is a plan view with the closure and diaphragm detached.

An automatic shut-off valve in accordance with this invention, comprises a flanged shell or casing 10, to which is attached at one side an intake 11, and to which is attached at its opposite side an outlet 12.

Integral with, and arranged within the shell 10, as well as being of less height than the height of the shell 10, is a partition 13, which divides the shell or casing 10 into three chambers, one of which is an inlet chamber 14 into which opens the intake 11, another is an outlet chamber 15 with which communicates the outlet 12, and the other of which is a diaphragm chamber 16, arranged over the inlet and outlet chambers and permanently in opened communication with the outlet chamber 15. Communication between the diaphragm chamber and inlet chamber is controlled through the medium of a valvular element to be presently referred to.

Arranged within the upper portion of the chamber 14, as well as secured to the wall of the latter, is a vertically disposed hollow cylindrical member 17' constructed of relatively soft metal and which has its lower edge bevelled to provide a valve seat 17, with which cooperates a valve 25, for the purpose of controlling communication between the intake chamber 14 and the diaphragm chamber 16.

The top of the casing or shell 10, is open and detachably mounted on the top of said shell or casing 10, is a flanged closure 19, and with the flange thereof opposing the flange of the shell or casing 10. Extending across the chamber 16, and interposed between the flanges of the shell and cover is a diaphragm 20, of relatively thin metal. The diaphragm 20, is secured to the cover and shell by hold-fast devices 18 which extend through the flanges of the cover and shell, as well as through the diaphragm 20, and the said hold-fast devices 18, further provide means for detachably connecting the cover to the shell. The diaphragm 20 is adapted to be expanded by the pressure of gas against its lower face.

Secured in the top of the member 17', projecting thereabove and having its upper end offset outwardly with respect to the member 17' is a supporting element 21, to which is eccentrically pivoted through the medium of the pivot pin 22, a lever 23, which extends over the member 17'. That end of the lever 23, which extends over the member 17' has pivotally connected therewith, as at 27, a depending valve stem 26, which carries on its lower end the valve 25. Carried by the other end of the lever 23, is a counter-weight 24.

Extending through the closure 19 and the diaphragm 20 is a push rod 28 having a push button 29 at the upper end externally of the closure. The rod 28 is pivoted at its lower end to the lever 23 between the pivot 22 and the weight 24, as at 30, and is provided with clamp nuts 31 and 32 where it passes through the diaphragm for securing it to the latter.

By this means the rod 28, diaphragm 20 and lever 23 are coupled to operate in unison as will be obvious.

Initially the rod 28 will be elevated to open the valve 25 and permit the gas to

flow into the gathering chamber 16 and thence through the outlet 12, the pressure of the flowing gas expanding the diaphragm 20 and holding the longer end of the lever 23 elevated against the pull of the weight 24 and correspondingly holding the valve 25 open and the burners lighted so long as the gas pressure continues.

If the flow of the gas ceases from any cause, and thus automatically extinguishes the burners, the reduction of pressure will cause the diaphragm to collapse and release the weight 24 and permit the latter to depress the longer end of the lever 23 and elevate the shorter end and close the valve and hold it closed.

When the flow of gas is resumed it will not pass to the extinguished burners until the valve is opened by pressure applied manually to the rod 28, which will of course, not take place until the burners are relighted.

A simply constructed device is thus produced by means of which the flow of gas to the burners cannot be resumed after being accidentally cut off until the attendant is ready to relight the burners, or given an opportunity to close the burners.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention what is claimed as new is:—

An automatic gas shut-off comprising a casing provided with a partition to form an inlet, an outlet and a diaphragm chamber, the latter being arranged over said inlet and outlet chambers and permanently communicating with the outlet chamber, a diaphragm secured with said casing and extending across the diaphragm chamber, a hollow cylindrical member secured in the upper portion of said inlet chamber and having its lower end constituting a valve seat, a supporting element secured in the top of and having its upper end offset with respect to said member, a lever eccentrically pivoted to the upper end of said element and arranged over said inlet and outlet chambers, a valve stem extending through said member and having its upper end pivotally connected to one end of said lever and its lower end provided with a valve cooperating with said seat for opening and closing said inlet chamber with respect to said diaphragm chamber, a counter-weight secured to the other end of said lever, and a vertically disposed push rod pivotally connected to said lever between its pivot and said seat and further connected to said diaphragm and extended from said casing.

In testimony whereof, we affix our signatures hereto.

JOSEPH G. HARRIS.
GEORGE D. JAQUETT.
